(57) CLAIM

The ornamental design for a chest of drawers, as shown and described.

DESCRIPTION

FIG. 1 is a top perspective view of a chest of drawers showing our new design;

FIG. 2 is a top plan view thereof;

FIG. 3 is a front elevation view thereof;

FIG. 4 is a side elevation view thereof, the opposite side being a mirror image thereof; and,

FIG. 5 is an enlarged sectional view taken along line 5—5 of FIG. 3.

The bottom and rear views (not shown) form no part of the claimed design.

The broken line subject matter is for illustrative purposes only and forms no part of the claimed design.

1 Claim, 5 Drawing Sheets
